DESIGN FOR A TABLE

Hazel Dell Brown, Lancaster, Pa.

Application September 21, 1935, Serial No. 58,636

Term of patent 3½ years

To all whom it may concern:

Be it known that I, Hazel Dell Brown, a citizen of the United States, residing at 218 East Orange Street, Lancaster, county of Lancaster, Commonwealth of Pennsylvania, have invented a certain new, original, and ornamental Design for a Table, of which the following is a specification, reference being had to the accompanying drawing, forming a part thereof, and in which the figure is a perspective view of the table, showing my design.

The drawing shows but one side of the table; the other side being of the same design as that shown.

I claim:

The ornamental design for a table as shown and described.

HAZEL DELL BROWN.
